US00D494078S1

(12) United States Design Patent (10) Patent No.: **US D494,078 S**
Vuillermoz (45) Date of Patent: **** Aug. 10, 2004**

(54) CURRENT SENSOR

(75) Inventor: **Guy Vuillermoz**, Bonne sur Menoge (FR)

(73) Assignee: **Liaisons Electroniques-Mecaniques LEM S.A.**, Geneva (CH)

(**) Term: **14 Years**

(21) Appl. No.: **29/173,977**

(22) Filed: **Jan. 9, 2003**

(30) **Foreign Application Priority Data**

Jan. 7, 2003 (WO) DM/062779

(51) LOC (7) Cl. **10-04**

(52) U.S. Cl. **D10/75**

(58) Field of Search ..... D10/75, 79, 80; 324/117 R, 117 H

(57) **CLAIM**

The ornamental design for a current sensor, as shown and described.

DESCRIPTION

FIG. 1a is a front perspective view of a current sensor showing my new design; and,

FIG. 1b is a rear perspective view of FIG. 1a.

1 Claim, 1 Drawing Sheet
